COMBINED FLASHLIGHT AND DETACHABLE SKELETON MASK THEREFOR

Perry Feuer, Roslyn, N.Y., assignor to Creative
Creations, Inc., New York, N.Y.

Original design application Feb. 25, 1971, Ser. No.
119,075. Divided and this application May 15,
1972, Ser. No. 253,698

Term of patent 14 years

Int. Cl. D26—02

U.S. Cl. D48—24 A

FIG. 1 is a front perspective view of a combined flashlight and detachable skeleton mask therefor showing my new design;

FIG. 2 is an exploded view thereof;

FIG. 3 is a front elevational view thereof, and

FIG. 4 is a side elevational view thereof with the flashlight being omitted for convenience of illustration.

This is a division of design application Ser. No. D. 119,075, filed Feb. 25, 1971.

I claim:

The ornamental design for a combined flashlight and detachable skeleton mask therefor, as shown and described.
